(57) **CLAIM**

The ornamental design for, a wheel for an automobile, as shown and described.

DESCRIPTION

FIG. 1 is a front side perspective view of a wheel for an automobile, showing my new design;

FIG. 2 is an enlarged partial front side perspective view thereof; and,

FIG. 3 is a font view thereof.

The broken lines shown in the drawings illustrate portions of the wheel for an automobile that are environmental structures and form no part of the claimed design.
